UNITED STATES PATENT OFFICE.

THOMAS HENRY HARRIS, OF FREDERICKSBURG, VIRGINIA.

PLOW.

SPECIFICATION forming part of Letters Patent No. 731,359, dated June 16, 1903.

Application filed March 9, 1903. Serial No. 146,922. (No model.)

To all whom it may concern:

Be it known that I, THOMAS HENRY HARRIS, a citizen of the United States, residing at Fredericksburg, in the county of Spotsylvania and State of Virginia, have made certain new and useful Improvements in Plows, of which the following is a specification.

My invention is an improvement in plows, and especially in disk plows and that class of such plows wherein a wheel-carriage is provided for supporting the disk-carrying devices; and the invention consists in certain novel constructions and combinations of parts as will be hereinafter described and claimed.

In the drawings, Figure 1 is a top plan view of a plow embodying my invention. Fig. 2 is a vertical longitudinal section thereof. Fig. 3 is a rear elevation of the plow. Fig. 4 is a top plan view, Fig. 5 a rear elevation, and Fig. 6 a partial top plan view of a somewhat different construction of plow within the broad principles of my invention. Fig. 7 is a detail perspective view illustrating the construction employed in the plow shown in Fig. 4 for supporting and adjusting the disk-shaft, and Fig. 8 is a detail cross-section on about the line 8 8 of Fig. 7.

Referring now to the construction shown in Figs. 1 and 3, it will be noticed that I employ a frame A, supporting the movable parts of the device, and to which the tongue B may be connected in any suitable manner. As shown and as may be preferred, the frame A is fitted upon the rear end of the tongue B and may be provided with the side flanges lapping alongside the said beam, as shown in Fig. 2. This frame A is provided at its rear end with bearings A', in which is slidably supported the crank-axle C, so the frame can be moved longitudinally along the crank-axle C in the operation of the device, as will be presently described. The axle C is provided at its opposite ends with the reversely-projecting cranks C', supporting the wheels C², and an arm or lever C³ is secured to the axle, as shown at C⁴, and can be operated to turn the axle, and thus adjust the same from the position shown in Fig. 3, for instance, to that indicated in dotted lines in the same figure, a rack A² being provided on the frame A for use in securing the arm or lever C³ in any desired adjustment. The shifting-shaft D is

journaled in bearings D' on the frame A, is provided at its front end with a handle or lever D², operating in connection with a rack A³ on the frame A, by which said lever may be secured in any desired adjustment, and the shaft D is provided at its rear end with a crank D³, to which is connected one end of a link D⁴, whose other end connects at D⁵ with the crank-axle C, so the turning of the shaft D may operate to shift the frame A and the parts carried thereby along the axle C in order to adjust the disk presently described to operate at any desired point. The disk E is supported on an arm F of the disk-shaft F. This shaft F is supported on the frame A in such manner that it may be turned to adjust the disk E from the position shown in Fig. 1 to that indicated in dotted lines in the same figure, or vice versa, and may be raised or lowered to set the disk into or out of position to cut a furrow in the ground. In the construction shown and as preferred the shaft F is journaled at its front end in a bearing G, so formed as to permit the said shaft to turn, and also to permit the shaft to be raised and lowered at its rear end, as will be understood from Figs. 1 and 2 of the drawings. At or near its rear end the main frame is provided with an upright guide-stand H, within which operates the disk-shaft F, so said shaft can be raised and lowered, as will be understood from Fig. 2. To this stand H, near its upper end, is journaled a shaft I, having a crank I', connected by means of a pitman or link I² with the shaft F, so that shaft I may be turned by its handle I³ to raise and lower the shaft F at the rear end of the latter. The handle I³ of the shaft I may be held in any desired adjustment by the rack A⁴, mounted on the stand H, as shown in Figs. 1, 2, and 3, so the shaft F may be secured in position to hold the disk out of the ground or in the ground to any desired extent. A handle lever or arm J is secured to the shaft F, preferably in advance of the stand H, and may be operated to turn said shaft in order to adjust the disk E to its different positions, catches J' being provided on the main frame in position to secure the lever J in either of its adjustments, as will be understood from Fig. 1 of the drawings. The shaft F has its disk-carrying arm F' projecting from its rear end forwardly and

at an incline, so it will support the disk E at the desired inclination to the line of draft, so the disk when set from side to side may be adjusted to operate either as a right or left plow. In the operation of the described construction it will be noticed I provide means whereby the operator can when sitting in the seat K adjust the crank-axle C by turning the same to raise and lower either side of the machine, can raise and lower the disk, can turn the disk-supporting shaft so as to set the disk right or left, and can shift the main frame along the crank-axle to secure the desired relation between the disk and the wheels in order to form the furrow in the proper place. I thus provide an implement by which the land-furrow may be turned in either direction, by which the depth of the furrow may be regulated as well as the width of such furrow and in which the disk can be lifted for passing over stones and other obstructions and in moving from one place to another, and in the use of which the driver can adjust his plow from the driver's seat and can begin work as soon as the team is in position in the field. Manifestly the axle may be long enough to properly support two or more disks, as may be desired.

In the construction shown in Figs. 4 to 8, inclusive, I present a somewhat different construction, whereby to secure the results before described. In this construction I employ a crank-axle similar to that shown in Figs. 1 to 3, such crank-axle 1 supporting the wheels 2 and having connected therewith a lever 3, by which the crank-axle may be turned, such lever 3 being jointed at 4 to a cuff 5 on the axle 1, so the lever may be turned to the position shown in Fig. 5 to clamp the axle when it is desired to turn the axle 1. This lever 3 also has at 6 a notch to receive a lug 7, projecting from a lever 8, which connects with the disk-shaft 9 and which operates to shift the disk-shaft and the main frame carrying the same along the axle 1. In this construction the main frame includes an upper plate 9 and a lower plate 10 in the form of castings and embracing the tongue 11, the lower casting 10 having a bearing at 12 for the axle 1 and the castings 9 and 10 having upright guides 13 for the uprights 14, carrying the driver's seat 15, such uprights extending at their lower ends below the casting 10 and being provided at 16 with a bearing for the disk-shaft 17, which disk-shaft may be raised and lowered at its rear end by means of the crank 18 on the shaft 19, the latter having a handle 20 at its front end and having its crank 18 engaging in a suitable one of a series of holes 21 in a plate 22, which is provided at 23 with an opening receiving the disk-shaft 17, so the latter can be raised and lowered at its rear end.

Manifestly in the construction shown in Figs. 4 to 8, inclusive, the disk-shaft may be reversed from side to side by means of the lever 8, the axle 1 may be turned by the le-

ver 3, and the frame be adjusted along the crank-axle in a manner somewhat similar to that shown in Figs. 1 to 3 and before described. It will also be understood that the construction shown in Figs. 4 to 8, inclusive, may be employed without departing from some of the broad principles of my invention.

Having thus described my invention, what I claim as new, and desire to secure by Letters Patent, is—

1. The herein-described plow, comprising the frame, the crank-axle along which said frame may slide, the wheels on said axle, the shifting-shaft journaled to the frame, and having a crank connected with the crank-axle whereby to shift the frame along said axle, the upright guide-stand on the frame, the disk-shaft provided at its rear end with a forwardly-inclining arm for the disk, and journaled at its front end to the frame and movable vertically between its ends in the guide-frame, the shaft on the guide-stand and having a crank connected with the disk-shaft to lift the same, the disk on the forwardly-inclined arm of the disk-shaft, means for rocking the disk-shaft, and means for rocking the crank-axle, substantially as set forth. 95

2. An implement substantially as described, comprising a disk, and a support therefor, consisting of a shaft having its front end journaled and its rear end movable vertically and provided at such end with a forwardly-inclined arm for carrying the disk, and devices for adjusting the rear end of the disk-shaft vertically, substantially as set forth. 100

3. The combination of the frame, the disk-shaft journaled at its front end and rockable and adjustable vertically at its rear end, and the disk carried by the rear end of the shaft, substantially as set forth. 105

4. The combination of the frame, the disk-shaft journaled at its front end and provided in rear of the journal with a forwardly-inclined arm, the disk on said arm, means for adjusting the rear end of the shaft vertically, and means for rocking the shaft in its front journal, substantially as described. 110

5. The combination with the frame, of the disk-carrying shaft journaled at its front end, means for rocking the shaft in said journal, and means connected with the frame for adjusting the rear end of the shaft vertically with respect to the frame. 115

6. The combination with the frame and the guide-stand thereon, of the disk-shaft movable and guided at its rear end vertically in the guide-stand, a bearing for the front end of said shaft, means for rocking the shaft and means for adjusting the rear end of the shaft vertically in the guide-stand, substantially as set forth. 125

7. The combination with the frame and the guide-stand, of the disk-shaft movable vertically in the guide-stand, a crank supported by the guide-stand above the disk-shaft, and connections between the crank and the disk- 130

shaft, whereby the crank may operate to adjust the said shaft vertically, substantially as set forth.

8. The combination in an implement substantially as described, of the frame, the crank-axle supporting the frame, means for shifting the frame along the crank-axle, means for turning the crank-axle, the disk - carrying shaft journaled to the frame and movable vertically therein, and means for rocking the disk-shaft and for adjusting the same vertically, substantially as set forth.

9. The combination with the axle, of the main frame movable along the same, the shifting-shaft journaled to the frame and having a crank, means for turning the shaft, and a connection between said crank and the axle, whereby the frame may be shifted along the axle, substantially as set forth.

10. The combination with the frame and the guide-stand, of the crank supported on the guide-stand, the arm or lever for swinging the crank, the rack on the stand for holding said arm with its crank in any desired adjustment, the disk-shaft movable vertically in the guide-stand and journaled at its front end to the frame, connections between the crank and the said shaft whereby the latter may be raised and lowered, means for turn-

ing the shaft, the crank-axle along which the frame may be moved or shifted, and means for shifting the frame along the axle, substantially as set forth.

11. The combination with the crank-axle and the frame movable along the same, of means for shifting the frame along the axle, whereby to secure the desired line of cut, means for turning the axle whereby to raise and lower the opposite wheels, the disk-carrying shaft supported on the frame, means for raising and lowering said shaft, and means for turning the same, substantially as set forth.

12. The combination of the frame, the upright guide-stand, the crank-axle along which the frame may be shifted, the shaft D journaled to the frame A and having a crank D² connected with the axle, the disk-shaft, the bearing G on the frame for said shaft, the guide-stand H on the frame, the crank carried by the guide-stand H and connected with the disk-shaft, and means for rocking the crank-axle, substantially as set forth.
